CLEVELAND CAR SPECIALTY COMPANY, OF CLEVELAND, OHIO, A CORPORATION OF
OHIO.

CAR-ROOF.

1,044,732.

Specification of Letters Patent.

Patented Nov. 19, 1912.

Application filed April 29, 1912. Serial No. 693,786.

To all whom it may concern:

Be it known that we, WILLIAM S. BIDLE and JOSEPH A. COSTELLO, citizens of the United States of America, residing at Cleveland, in the county of Cuyahoga, State of Ohio, have invented certain new and useful Improvements in Car-Roofs; and we do hereby declare the following to be a full, clear, and exact description of the invention, such as will enable others skilled in the art to which it pertains to make and use the same.

Our invention relates to improvements in car-roofs, and pertains more especially to an improved car-roof-construction for a railway-car.

The primary object of this invention is not only to employ a carline or other supporting member in supporting two metal roofing-sections and to have said roofing-sections extend from over said carline or supporting member laterally of said member in opposite directions and connected together by a cap, but to have adjacent portions of said roofing-sections so contoured in cross-section and relatively arranged as to prevent buckling or distortion of said roofing-sections by the racking and weaving of the car.

With this object in view, and to the end of attaining other advantages hereinafter appearing, this invention consists in certain features of construction, and combinations and arrangement of parts, hereinafter described, pointed out in the claims, and illustrated in the accompanying drawing which is a view partly in section and partly in perspective of a portion of a car-roof embodying our invention.

Referring to said drawing, A indicates a steel trough forming a carline of our improved car-roof. The application of carlines in the construction of car-roofs is too well known in the art to require illustration and description in this specification. The trough A is adapted to extend between and be connected to the side plates (not shown) of a car-roof. Said trough is provided at its top and externally with two laterally and outwardly projecting flanges *a* and *a* which are arranged at opposite sides respectively and extend longitudinally of the trough.

Two metal roofing-sections B and B rest on opposite flanges *a* and *a* respectively.

Said roofing-sections extend from over the carline-trough A laterally of said carline-trough in opposite directions.

Each of the roofing-sections B is provided between the flanges *a* and *a*—that is, between the sides of the carline-trough A,—with an ogee-curved member 3 which depends into and extends longitudinally of said trough, and said curved members of said roofing-sections are spaced apart and from the sides of said trough. The lower portion of each of said ogee-curved members of said roofing-sections forms a trough 4 which is arranged within and extends longitudinally of the carline-trough A. Said troughs 4 of said roofing-sections are spaced apart and from the sides of said carline-trough, and adjacent walls or portions of said troughs of said roofing-sections are extended upwardly and toward each other and form upwardly projecting side members *b* of said roofing-sections, and said side members of said roofing-sections have their lower portions spaced apart and have their upper portions abutting against each other, as at 5, and terminating in laterally and outwardly projecting resilient arched flanges 6. Said side members *b* of said roofing-sections have their lower portions inclined upwardly and toward each other. It will be observed that said side members *b* of said roofing-sections, being formed by adjacent walls or portions of the troughs 4 of said roofing-sections and by the upward extension of said walls or portions of said troughs, depend into the carline-trough A so as to insure the dripping into said carline-trough of any water having access to and running adown the opposing surfaces of said side members of said roofing-sections. It will be observed also that the downward divergence of said side members *b* of said roofing-sections from their abutting portions and the ogee-curved members 3 of said roofing-sections not only accommodate expansion and contraction of said roofing-sections but prevent buckling or distortion of said roofing-sections during the racking and weaving of a railway car provided with our improved roof. A metal cap C covers said side members *b* of said roofing sections and incloses the flanges 6 and presses against the outer sides of the outer portions of said flanges and holds said side members together, and said cap is provided

with laterally and outwardly projecting flanges 7 which rest on the bodies of said roofing-sections over the flanges of the carline-trough A.

5 By our improved construction any water driven or forced into the cap C from next below the flanges of said cap and received by the troughs 4 of the roofing-sections can be conducted off by said troughs, and any 10 water which may perchance be driven or forced to and over the flanges 6 of the aforesaid side members b of said roofing-sections and thence pass downwardly between the abutting upper portions of said side members is caused to drip into the carline-trough A. 15 Not unimportant, also, is such an arrangement, as shown of the outer downwardly projecting portion of the arched flange 6 of each roofing-section that the inner side 20 of said portion of said flange is over the ogee-curved portion or member 3 of said roofing-section, and consequently over the trough 4 of the said roofing-section, so that any water dripping from said side of said 25 portion of said flange shall be received and conducted off by said trough.

What we claim is:—

1. The combination, with a carline comprising a trough, of two metal roofing-sections extending from over said carline-trough laterally of the carline-trough in opposite directions, each of said roofing-sections having a side member which extends into and longitudinally of said carline-trough, and projects upwardly from within said carline-trough said side members of said roofing-sections having their lower portions spaced apart, and a cap covering said side members.

40 2. In a car-roof, two adjacent metal roofing-sections provided each with an upwardly projecting side member, said side members of said roofing-sections having their lower portions spaced apart and their upper portions terminating in laterally and outwardly projecting arched flanges, each roofing-section having an ogee-curved portion terminating in the lower portion of the aforesaid side member of said roofing-section, and a 45 cap inclosing said flanges, the downwardly projecting outer portion of the arched flange of each roofing-section having its inner side arranged over the ogee-curved portion of said roofing-section.

55 3. The combination, with a carline comprising a trough, of two metal roofing-sections extending from over the carline-trough laterally of the carline-trough in opposite directions, each of said roofing-sections having a trough-forming member extending longitudinally of the carline-trough between the sides of carline-trough, said trough-forming members of said roofing-sections being spaced apart centrally between the 60 sides of the carline-trough and there ex-

tended upwardly and forming upwardly projecting side members of said roofing-sections, and a cap covering said side members.

4. The combination, with a carline comprising a trough, of two metal roofing-sections extending from over the carline-trough laterally of the carline-trough in opposite directions, each of said roofing-sections having a trough-forming member arranged within and extending longitudinally of the carline-trough between the sides of the carline-trough, adjacent portions of the trough-forming members of the roofing-sections being extended upwardly and forming upwardly projecting side members of said roofing-sections, and a cap covering said side members of said roofing-sections.

5. The combination, with a trough, of two metal roofing-sections extending from over said trough laterally of the trough in opposite directions, each of said roofing-sections having a trough-forming member arranged within and extending longitudinally of the aforesaid trough between the sides of said trough, said trough-forming members of said roofing-sections being spaced apart and from the sides of said trough, and adjacent portions of said trough-forming members being extended upwardly and forming upwardly projecting side members of said roofing-sections, and a cap covering said side members of said roofing-sections.

6. The combination, with a carline comprising a trough, of two metal roofing-sections extending from over the carline-trough laterally of the carline-trough in opposite directions, each of said roofing-sections having an ogee-curved member extending longitudinally of the carline-trough said ogee-curved members of said roofing-sections being spaced apart centrally between the sides of the carline-trough and there extended upwardly and forming upwardly projecting side members of said roofing-sections, and a cap covering said side members.

7. The combination, with a carline comprising a trough, of two metal roofing-sections extending from over the carline-trough laterally of the carline-trough in opposite directions, each of said roofing-sections having an ogee-curved member depending into and extending longitudinally of the carline-trough, adjacent portions of said ogee-curved members being extended upwardly and forming upwardly projecting side members of said roofing-sections, and a cap covering said side members.

8. The combination, with a trough, of two metal roofing-sections extending from over said trough laterally of the trough in opposite directions, each of said roofing-sections having an ogee-curved member depending into and extending longitudinally of said trough, said ogee-curved members of said roofing-sections being spaced apart and

from the sides of the said trough, and adjacent portions of said ogee-curved members being extended upwardly and forming upwardly projecting side members of said roofing-sections, and a cap covering said side members of said roofing-sections.

9. The combination, with a carline comprising a trough, of two metal roofing-sections extending from over the carline-trough laterally of the carline-trough in opposite directions, each of said roofing-sections having a trough-forming member extending longitudinally of the carline-trough between the sides of the carline-trough, said trough-forming members having their adjacent sides extended upwardly, and a cap covering said trough-forming members.

10. The combination, with a carline comprising a trough, of two metal roofing-sections extending from over the carline-trough laterally of the carline-trough in opposite directions, each of said roofing-sections having a trough-forming member extending longitudinally of the carline-trough, said trough-forming members being extended at their adjacent sides into contact with each other above the carline-trough, and a cap covering said trough-forming members.

11. The combination, with a carline com-

prising a trough, of two metal roofing-sections extending from over the carline-trough laterally of the carline-trough in opposite directions, each of said roofing-sections having an ogee-curved member extending longitudinally of the carline-trough, said ogee-curved members being extended into contact with each other, and a cap covering said ogee-curved members.

12. The combination, with a carline comprising a trough, of two metal roofing-sections extending from over the carline-trough laterally of the carline-trough in opposite directions, each of said roofing-sections having an ogee-curved member extending longitudinally of the carline-trough, adjacent portions of said ogee-curved members being extended upwardly and forming upwardly projecting members which abut laterally against each other over the carline-trough, and a cap covering said upwardly projecting members.

Signed by *me* at Cleveland, Ohio, this 23d day of April, 1912.

WILLIAM S. BIDLE.
JOSEPH A. COSTELLO.
